UNITED STATES PATENT OFFICE

THOMAS E. LANE, OF CAMBRIDGE, MASSACHUSETTS, ASSIGNOR TO LEVER BROTHERS COMPANY, OF CAMBRIDGE, MASSACHUSETTS, A CORPORATION OF MAINE

MACHINE FOR FEEDING INSERTS

Application filed January 29, 1929. Serial No. 335,838.

In the preparation of merchandise for the market it is frequently desirable to include an insert in the package or wrapper in which the merchandise is enclosed, such an insert consisting of a slip of paper bearing advertising matter, directions for using merchandise, or other information. Most merchandise is now packaged or wrapped by automatic machinery and it is preferable, therefore, to introduce inserts of the character just mentioned by automatic mechanism. To devise a simple and reliable machine for performing this function constitutes the chief object of this invention.

16 The nature of the invention will be readily understood from the following description when read in connection with the accompanying drawings, and the novel feature will be particularly pointed out in the appended 20 claims.

In the drawings,

Figure 1 is a perspective view of an insert feeding machine constructed in accordance with this invention and applied to a carton filling machine;

Fig. 2 is a side elevation of the insert feeding machine shown in Fig. 1, and shows, in section, adjacent parts of the carton filling machine;

30 Fig. 3 is a rear elevation of the insert feeding machine shown in Figs. 1 and 2;

Fig. 4 is a plan view of said machine; and

Fig. 5 is a vertical sectional view substantially on the line 5—5, Fig. 2.

35 Referring first to Figs. 1 and 2, the carton filling machine partly shown in these figures is of a well known type and includes a conveyor belt 2 on which a series of cartons C rest and are fed forward. A guideway comprising rails 3—3 laterally supports and guides the entire series of cartons on the belt. The rails 3—3 are adjustably supported in brackets 4—4 carried by side rails 5—5. Referring to Fig. 1 it will be observed that the

40 forward movement of the cartons in this guideway is limited by a stop 6, and that a plunger 7 arranged to be operated by a lever arm 8 is provided to push the cartons laterally off the conveyor 2 and out of the guideway. This general arrangement is common

in several makes of carton filling machines found on the market.

The insert feeding machine shown in the drawings is arranged to feed inserts one at a time into the cartons as they come into a predetermined relationship in the plunger 7. This machine comprises a frame piece 10 supported on one of the side rails 5 and side brackets 12—12 bolted to the frame piece. The upper ends of the bracket members 12—12 are connected by a cross piece 13 and two blocks 14 and 15, respectively, are bolted to the upper surface of this cross piece. Similar blocks are mounted on the upper end of the frame piece 10 and on the support 11, and the three sets of blocks cooperate to support a horizontal magazine for holding a supply of inserts to be fed into the cartons. The floor of this magazine consists of three metal strips or bars 16 on which the inserts I rest 70 and the magazine also includes side rails 17—17 for laterally supporting the inserts. Preferably the block 15 is secured in place by a screw 18, Fig. 5, which extends through a slot 19 formed in the cross piece 13 so that 75 it can be adjusted toward or from the opposite side piece, and the corresponding blocks at the front and rear ends of the magazine are similarly mounted, provision thus being made for adjusting the width of the magazine to accommodate inserts of different lengths. The rearward end of the magazine may be supported by a curved post or pedestal 19.

80 The entire series of inserts in the magazine is urged forward by a follower 20 which is slidably mounted in the magazine and is pulled forward by two weights 21—21, Figs. 3 and 4, which are connected with the opposite ends of the follower by cords 22—22 running over pulleys 23 and 24. The front surface of the follower 20 is inclined, as best shown in Fig. 2, so that it tends to hold the inserts in the entire series in an inclined position.

85 This follower exerts considerable pressure on the inserts and in order to hold them down on the rails 16 and prevent them from bulging upwardly, two horizontal rods 25—25 are arranged to rest on the upper edges of the inserts. At the forward end of the maga- 100

- zine these rods are welded to a cross shaft 26 which is mounted in clips 27-27 adjustably secured by screws 28-28 to the opposite sides of the magazine. The rearward ends of the 5 rods 25-25 are welded to a cross rod 30 which normally rests in the upper forked ends of two slotted clips 31-31 adjustably secured by screws 32-32, respectively, to the opposite sides of the magazine.
- 10 This construction permits the rearward ends of the rods 25-25 to be raised when it is necessary to replenish the supply of inserts in the magazine, the rods swinging about the axis of the cross shaft 26. Normally, however, the rods are locked in their 15 horizontal positions by a hold-down device comprising a hook 34 formed on the forward end of a sleeve 35 which is mounted to slide vertically on a rod 36 and normally is pressed downwardly by a coiled spring 37 enclosed in the sleeve and surrounding the rod. A handle 38 projects rearwardly from the sleeve and may conveniently be grasped in order to lift the hook off the cross rod. The rod 36 20 extends into and is secured to a part 40 which is fulcrumed at 41 in ears projecting rearwardly from the part 11.
- The inserts are fed out of the forward end of the magazine one at a time by means of 30 one or more friction feed wheels. In the construction shown three feed wheels 43 are used, the surface of each wheel consisting of knurled rubber and all three wheels being secured fast to but adjustably on a horizontal 35 shaft 44. A ratchet wheel 45 is secured on one end of this shaft and is arranged to be fed intermittently by a spring pressed pawl 46 carried by an arm 47 which is mounted to rock on the shaft 44. A link 48 connects 40 the upper end of this arm with a block 50, Figs. 3 and 4, which is adjustable longitudinally in a slot 51 formed in an operating lever 52 mounted to rock on the shaft 53. The lower end of this lever is forked and 45 machined to receive slidably a block 54 in which a stub shaft 55 is mounted, this shaft being secured to and projecting laterally from the upper end of the lever 8, previously referred to.
- 50 In order to prevent the feeding of more than one insert at a time, three gates, one for each of the feed wheels 43, are arranged immediately below the forward end of the magazine and in line with the respective feed 55 wheels. One of these gates is shown in Fig. 2 at 57. It comprises a metal piece provided with a recess in its upper surface in which a soft rubber pad 58 is secured. The gate is urged forward toward its feed wheel by a spring 60, and it is guided partly by a metal piece 61 mounted on the upper end of the 60 frame piece 10 and partly by a stem 62 which projects rearwardly from the gate 57 and slides through one of the blocks that supports 65 the magazine rails. Movement of the gate

toward the feed wheel under the influence of the spring 60 is limited by nuts 63 threaded on the stem 62.

When the machine is in operation the follower 20 urges the entire series of inserts I 70 toward the front of the magazine and tends to hold the foremost insert in the series in contact with the feed wheels 43. Each time that the plunger 7 forces one of the cartons C laterally out of the guideway it also operates 75 to give the feed wheels 43 a feeding movement, this motion being transmitted through the lever 52, link 48 and pawl 46. The knurled rubber surfaces of the wheels, acting on the foremost label, carry it downward- 80 ly out of the magazine and past the gates 57. At this time a carton is positioned directly in front of the insert feeding machine so that the insert so fed out of the magazine drops into the upper open end of the carton. As 85 soon as the plunger 7, Fig. 1, withdraws, the belt 2 moves the entire series of cartons forward again and thus positions another carton in readiness to receive an insert. Sufficient friction is applied to the feed wheel 90 shaft to prevent any backward rotation of the feed wheels when the plunger moves rearwardly. The inserts at the front of the magazine are held down partly by the rods 25 and also by a roll 64 mounted on the shaft 26. A wire guide 65, Fig. 2, also may be provided to assist in directing each insert as it is fed out of the magazine into the top of the carton. The rubber pieces 58 in the 95 gates 57 effectually prevents the feeding of more than one insert at a time due to the frictional resistance which they apply to the insert immediately behind the one on which the feed wheels are acting. A fairly accurate adjustment of the gate is necessary for this 100 purpose, and such an adjustment is easily obtained by the setting of the nuts 63. It will be observed that any insert must be fed out of the magazine against the frictional drag applied by the rubber members 58 to 105 the surface of the insert opposite to that engaged by the feed wheels. The drag so applied is very appreciable and since the insert immediately behind the one being fed tends to move with the latter solely through 110 contact with it, the feeding movement so applied is not sufficient to overcome the resistance applied by the rubber tips 58.

Whenever the supply of inserts becomes 115 depleted the hook 34 is lifted off the rod 30, the rods 25-25 are raised, the follower 20 drawn backwardly, and an additional supply is placed between the follower and the series of inserts remaining in the magazine. The rods 25-25 are then returned to their normal positions.

The invention thus provides a relatively simple mechanism for feeding inserts, the machine can be manufactured economically, has a high degree of reliability, and requires 120 125 130

relatively little attention. It has been illustrated in connection with a carton filling and sealing machine since it is frequently used in this relationship, but it will be understood 5 that the machine can be used in other relationships. It may be pointed out, however, that it is of advantage to drive the feed wheels 43 from the plunger 8 when the mechanism is applied to a carton filling machine or the like, since this arrangement provides a convenient means for timing the operation of the insert feeding mechanism. Usually, also, carton filling and sealing machines are so organized that if the feeding 10 of the cartons is stopped for any reason the operation of the plunger which acts on the cartons also is stopped. By deriving the insert feeding movement from the plunger, therefore, the mechanism always remains 15 properly timed with the handling of the cartons.

While I have herein shown and described a preferred embodiment of my invention, it will be understood that the invention may 20 be embodied in other forms without departing from the spirit or scope thereof.

Having thus described my invention, what I desire to claim as new is:

1. In a machine of the character described, 30 the combination of a guideway for a series of cartons; a plunger for pushing the cartons transversely off said guideway; mechanism for delivering an insert to each carton, said mechanism comprising a magazine for holding 35 a supply of said inserts, a friction feed wheel for engaging the foremost insert in the magazine and feeding it out of the magazine, and a friction gate cooperating with said feed wheel to prevent the feeding of more than one 40 insert at a time; and lever and link connections between said plunger and feed wheel for operating the feed wheel.

2. In a machine of the character described, 45 the combination of a guideway for a series of cartons; a plunger for pushing the cartons transversely off said guideway; mechanism for delivering an insert to each of said cartons as they arrive, respectively, in a predetermined 50 relationship to said plunger; said mechanism comprising a substantially horizontal magazine for holding a supply of inserts, a friction feed wheel for engaging the foremost insert in the magazine and feeding it out of the magazine, and an adjustable 55 gate positioned closely adjacent to and in alinement with said feed wheel for preventing the feed of more than one insert at a time; and connections between said feed wheel and said plunger for operating the feed wheel inter- 60 mittently.

3. In a machine of the character described, 65 the combination of a guideway for a series of cartons; a plunger for pushing the cartons transversely off said guideway; mechanism for delivering inserts to the cartons on said

guideway comprising a magazine for holding a supply of said inserts, and means for engaging the foremost insert in the magazine and feeding it out of the magazine; and adjustable lever and link connections between 70 said plunger and said feeding means for operating the feeding means.

4. In a machine of the character described, 75 the combination of a guideway for a series of cartons; a plunger for pushing the cartons transversely off said guideway; mechanism for delivering inserts to the cartons on said guideway comprising a magazine for holding a supply of said inserts and means for engaging the foremost insert in the magazine and feeding it out of the magazine; and adjustable lever and link connections between 80 said plunger and said feeding means including a pawl and ratchet mechanism through which said plunger is operative to actuate said feeding means.

5. In an insert feeding mechanism, 85 the combination of a magazine for holding a supply of inserts, a friction feeding wheel for engaging the foremost insert in said magazine and feeding it out of the magazine, said magazine including a bar on which the inserts rest and said bar having a bevelled end positioned closely adjacent to said feed wheel, a gate mounted immediately below said bar 90 and having a part made of rubber to engage the face of each insert opposite to that engaged by the feed wheel as the inserts are fed one at a time out of the magazine, means supporting said gate for movement toward and from said wheel in a direction approximately parallel to said bar, a spring for pressing said gate forward in said direction toward said wheel, means cooperating with said spring for adjusting said gate backward or forward in 95 said direction relatively to said wheel, and mechanism for operating said feed wheel.
